UNITED STATES PATENT OFFICE.

PETER D. EVANS, OF DAYTON, OHIO.

DOOR-CONTROLLING MECHANISM.

Application filed May 23, 1921. Serial No. 471,606.

To all whom it may concern:

Be it known that I, PETER D. EVANS, a citizen of the United States, residing in Dayton, in the county of Montgomery and 5 State of Ohio, have invented certain new and useful Improvements in Door-Controlling Mechanism, of which the following is a specification, reference being had therein to the accompanying drawings.

10 This invention relates to door controlling mechanism, having particular reference to improvements in mechanism for automatically controlling opening and closing of doors to permit of ready entrance and exit 15 therethrough.

My invention in its general use is adaptable to the entrance and exit doors of stores; between departments of stores, factories, hospitals; between kitchens and dining rooms 20 of homes, hotels, restaurants, etc., the door controlling mechanism, with suitable modifications as to size and detail arrangements, being adaptable for and of great advantage as used with any swinging door, whether 25 single or double, where manual operation of the doors is difficult, or interference with the doors is likely to occur upon passing therethrough.

An object of my invention is to provide 30 door controlling mechanism which will permit of maintaining the floor of the door passageway substantially normal, that is to say, substantially flush with the adjacent floor, and which will have no projections 35 above the floor to interfere with the entrance or exit passages.

It is a further object of my invention to provide door controlling mechanism which will be entirely automatic, or in other words, 40 which will require no effort of those passing through the doors to open and close the same. It is an object of the invention to provide suitable stops and checks which will operate automatically to effect smooth control of the door, to eliminate slamming of the door and to minimize noise of operation.

These and other characteristics of my invention will be apparent from the following detailed specification and the accompanying drawings in which the invention is illustrated in one form of preferred construction for illustrative purposes, it being understood that it is contemplated in the practice of the invention to make such modifications 55 of the construction here shown as may be required to effect suitable applications of

the principle of the invention under the varied conditions of its commercial use, such changes or modifications being contemplated and comprised in the definition of 60 the invention in the appended claims.

In the drawings:

Fig. 1 is an elevation of double swinging doors having my invention in one form applied thereto; 65

Fig. 2 is a plan view of the lower portion of the door controlling mechanism taken on the section line 2-2 of Fig. 3;

Fig. 3 is an elevation of the mechanism taken in the direction of the arrow 3-3 of 70 Fig. 2, and

Fig. 4 is an end elevation of the mechanism taken in the direction of the arrow 4-4 of Fig. 2.

Fig. 1 of the drawings illustrates an application of my invention, as here shown, to two oppositely swinging doors 1-1, which represent respectively entrance and exit doors —2 representing the floor of the passageways, and the adjacent floors —3, a hand rail —4 between the entrance and exit passages, the doors being hung and swinging oppositely on any suitable mechanism as indicated by upper hinges —5 and lower hinges —6 —7 representing a panel between the doors, door latches —8, for fastening the doors closed, spring catches —9 for the doors in their closed position, spring catches —10 for the doors in their open position, a latch —12 for locking the door operating mechanism to hold the doors in open position, and strap hinges —11 extending across the bottom of the doors, thus to stiffen the construction. 85

The door controlling mechanism as illustrated in Figs. 2, 3 and 4 consists of a rectangular-shaped frame structure —B—b which is adapted to occupy, in two units for double doors, the spaces A—A as indicated in Fig. 1. Hinged on the frame B—b, here shown as at —13, is a horizontally disposed frame —C— of substantially smaller dimensions than the frame —B—, the frame —C— together with floor —2 laid thereon, being adapted to operate pivotally on the hinges —13 to the extent indicated by dotted lines —c in Figs. 3 and 4. Supported adjacent the opposite edge of frame —C in depending brackets —14 are longitudinally opposite rollers —15 which ride on forwardly projecting plates —16 secured to an actuating shaft —17 extending longitudinally of the 95 100 105 110

frames —B and —C and supported in opposite bearing brackets —b.

Actuating shaft —17 has secured thereto a yoke —18 which is connected to a sliding sleeve —19 on a shaft —20, a compression spring —21 being arranged telescopically of the shaft and having one of its ends butted against sleeve —19 and its opposite end against adjusting nuts —22 threaded on shaft —20, the end of the shaft having a link —23 secured thereto for connecting the shaft to a lever —24 which is pivoted at one end as indicated at —25 to one of the cross frames —b, and connected at its opposite end to a link —26 and by means of the link to an arm —27 secured to a vertical shaft —28 which forms the pivot member of the lower hinge —6 of door —1. Thus it will be seen that downward movement of frame —C will be effective through the described connections, to operate door —1 in one direction.

An adjustable tension spring —29 is connected at one end to lever —24 and at its opposite end to one of the longitudinal frames —b, and serves to hold the door operating parts in their normal relation when there is no weight, or insufficient weight, on frame —C to overcome the tension of the spring, provision being made as at —a and —a' to connect the spring on the opposite side of shaft —20. Spring —21 serves as a buffer spring to absorb shocks transmitted to the mechanism, and to compensate for variations in the movements of the door and adjustments of the mechanism. Also connected to lever —24, adjacent the connections to link —26, is a shaft —30 having a compound stop —31, operable through an aperture in the longitudinal frame —b, secured to its opposite end, resilient buffers —32—33, adjustable on shaft —30 as to their spacing relation relative to frame —b, being used, as here shown, to limit movement in both directions of the shaft, thus to determine the open and closed stop positions of the door and to absorb the shocks when the door swings free in either direction.

Frame —C is supported in front by two longitudinally opposite rollers —34 mounted on bell-crank levers —35 which are pivoted on vertical frame brackets —b, the opposite ends of the levers —35 having springs —36 connected thereto, the springs being secured at their opposite ends to base frame —B by means of brackets —37, the connection to the brackets being made by spring adjusting screws —38, this mechanism as a whole thus serving to further support frame —C at the front and to cooperate with the rollers —15 to maintain the frame balanced irrespective of the position or distribution of weight thereon, as for example, the weight of a person walking through the doorway.

Supported at the front central portion of frame —C is a spring latch mechanism comprising a depending frame —39, secured to frame —C, a latch —40 pivoted on frame —39 and having a beveled catch —41 projecting through a slot in frame —C and adapted to engage and hold the door closed, a spring —42 serving to hold the latch normally raised, the door as it swings shut striking the beveled edge —43 of the catch —41, will depress and ride over the catch and thus be engaged and retained by it in closed position.

In Fig. 4 latch mechanism for holding the door open is illustrated. The mechanism, as here shown, consists of a lever —44 which is pivoted at its central portion as at —45 and connected at one end by a link —46 to frame —C, the opposite end of the lever being free. Adjacent its opposite end lever —44 is connected through a slot —47 to a link —48 and by means of the link to a latch —49 which has an upwardly projecting catch —50 adapted to engage and hold the door open, a spring —51 serving to hold the latch normally raised, thus, when the door swings open, it will strike the catch —50, ride over it and be engaged by it in open position.

From the foregoing detailed description the construction and operation of my improved door operating mechanism will be readily understood. It will be seen that the mechanism can be readily adjusted for variable weight on the floor —2 for operating the door, as for example, the weight of children and of adults; the door remaining open as long as weight is on the floor —2, any number of persons can pass therethrough without interference with a swinging door as is the case with doors of the usual construction. Upon stepping on the floor —2 in the entrance passageway, the entrance door will swing inwardly and will be latched by the mechanism illustrated in Fig. 4; upon stepping off floor —2 on the opposite side of the door, the action of springs —21 and —36 will return the floor to its normal elevation, the latch mechanism being automatically released with the upward movement of frame —C, thus permitting the door to swing shut and be latched by the mechanism illustrated in Fig. 3. A latch 12, as illustrated in Figs. 1 and 3 is provided as here shown for securing floor —2 in its lowered position, thus serving to hold the door open as long as the latch is in engaged relation, and permitting the floor to rise and the door to close when the latch is disengaged. It will be observed that floor —2 has but slight operating movement, full operation of the door being effected by the compounded levers of the controlling mechanism. Objectionable off-sets between the operable floor —2 and fixed floor —3 are thus

avoided and entrance and exit through the door will in nowise be interfered with.

Having described my invention, I claim:

1. In door operating mechanism, the combination with a swinging door, of an operable floor adjacent the doorway, and connections between the door and floor whereby upon placing movable weight on the floor on one side of the door said door will be swung open and upon removing the weight on the other side of the door said door will be swung shut, and means other than said connections for retaining the door in said open and closed positions.
- 15 2. In door operating mechanism, the combination with a swinging door, of an operable floor extending through and beyond the doorway, and means for operating the door including a pivotally-operable supporting frame for the floor and connections between said frame and the door comprising an actuating shaft arranged longitudinally of the frame and roller supports for the frame operatively connected with said shaft whereby operative movement of the floor will effect opening and closing of the door.

3. In door operating mechanism and in combination with a normally closed door, an operable floor adjacent the doorway and normally flush with the adjacent floor, and means for operating the door including a pivotally-operable support for said floor and connections between the support and the door including a combination of levers and an adjustable compensating spring whereby operative movement of the floor will effect opening and closing of the door and variable movements of the door operating mechanism will be compensated for by said spring.

4. In door operating mechanism and in combination with a normally closed door, an operable floor adjacent the doorway, and means for operating the door including a pivoted frame and yieldable stop mechanism adjustable to compensate for variable movements of the door whereby operative movement of said floor will effect opening and closing of the door to limits of movement determined by said stop mechanism.

In testimony whereof, I affix my signature.

PETER D. EVANS.
